CIGAR HOLDER

Edward L. Redford, Elizabeth, N.J., assignor to Belgo International, Roselle, N.J., a partnership

Filed Mar. 25, 1963, Ser. No. 74,097

Term of patent 14 years

(Cl. D85—8)

The drawing is stippled to indicate a mottled surface ornamentation.

I claim:

The ornamental design for a cigar holder, as shown and described.
